UNITED STATES PATENT OFFICE.

J. FREEMAN MCKENNEY, OF BALTIMORE, MARYLAND.

SHUTTLE FOR SEWING-MACHINES.

SPECIFICATION forming part of Letters Patent No. 406,368, dated July 2, 1889.

Application filed July 9, 1887. Serial No. 243,864. (No model.)

To all whom it may concern:

Be it known that I, J. FREEMAN MCKENNEY, of the city of Baltimore, in the State of Maryland, have invented a certain new and useful Improvement in Shuttles for Sewing-Machines; and I do hereby declare that the following specification, with the drawings making a part of the same, is a full, clear, and exact description of the same.

- 10 In the class of sewing-machine shuttles known as "cylinder" or "cylindrical" bored shuttles, the outer surface has been made so nearly cylindrical in form that the motion of the shuttle and drawing of the thread cause 15 them to roll in the race, thus removing at times the point of the shuttle from the face of the race, with which it should always be in close contact, so that the shuttle sometimes fails to pass through the needle-loop and thus skip 20 stitches. This rolling of the shuttle also wears the face of the same to a rounding or cylindrical form, and also destroys the original curve of the shuttle-face, thus rapidly increasing the trouble.
- 25 The object of my invention is to furnish a cylindrically-bored shuttle which shall not be open to this objection; and with this object in view I will describe my shuttle.

My invention consists in providing a cylindrically-bored sewing-machine shuttle with a flat side or base upon the under part thereof, at an acute angle with the flat face of the shuttle, in such a manner that when the shuttle is in place in the machine the flat surface or base will rest in close contact with the flat surface of the shuttle-carrier in such manner as to prevent the shuttle from rolling in the race.

Figure 1 is a top plan view of so much of a 40 sewing-machine as is necessary to show the

shuttle in position for operation. Fig. 2 is a sectional view of the same parts, showing a section of the shuttle-carrier and face of the race in contact with the shuttle, as in Fig. 1. Fig. 3 is a view of the under or reverse side 45 of the shuttle, showing the flat surface or base.

In the drawings, A represents the shuttle in position in the machine, resting in the carrier B and against the curved shuttle-race a a.

C C is the bed of the machine, with the 50 slides, (shuttle-race covers,) the feed, and the thread-plate (needle-plate) removed to afford an uninterrupted view of the shuttle.

D, in Figs. 2 and 3, is the flat side or base designed to rest in contact with the shuttle- 55 carrier B.

Having thus described my invention, what I claim, and desire to secure by Letters Patent of the United States, is—

1. A sewing-machine shuttle having a cylindrically-bored barrel provided with a flattened face curved in the direction of the length of the shuttle, and a flattened bottom surface at an acute angle with the flattened face, as set forth. 60

2. The combination, with the shuttle-race having a flat curved side engaging the face of the shuttle, and a carrier having a flat surface engaging the bottom of the shuttle, as set forth, of a shuttle provided with a flattened face curved in the direction of its length, and a flattened bottom surface at an acute angle with said flattened face, as and for the purposes described. 70

In testimony whereof I affix my signature in 75 presence of two witnesses.

J. FREEMAN MCKENNEY.
